UNITED STATES PATENT OFFICE.

ETHURGE CRAVENS, OF WEST TULSA, OKLAHOMA.

STILL SCRAPER.

Application filed February 3, 1922. Serial No. 533,879.

To all whom it may concern:

Be it known that I, ETHURGE CRAVENS, a citizen of the United States, residing at West Tulsa, in the county of Tulsa and State of Oklahoma, have invented new and useful Improvements in Still Scrapers, of which the following is a specification.

This invention relates to attachments for stills used in refining oil and has for its object the provision of a continually acting power driven scraping mechanism forming a permanent part of the still and operating to eliminate the accumulation of carbon deposits and consequently prevent hot spots which result in causing buckling of the still, the device further operating to greatly increase the utility of the still in making it capable of longer use before taking down and hand cleaning is necessary.

It is well in the art that in the operation of stills either of the pressure or vacuum type used in refining oil, carbon deposits accumulate on the wall of the still and result in the formation of what is known as hot spots which cause the stills to buckle and make it necessary to shut down the still and make repairs with a considerable expenditure of time and labor. It is also well known that various types of mechanical devices which might be conceived would not operate in a still of this character owing to the presence of the carbon which would cause disintegration of the parts of many mechanical devices if an attempt were made to use them. With these facts in view I have designed the present device which has for an important object the provision of a constantly rotating device within the still carrying a plurality of scraper blades which are gravity operated and which engage against the still walls and scrape off the carbon deposit as it is formed, the device being furthermore of a spiral nature whereby to move all the sediment to the rear end of the still where the major portion of the sediment and carbon may be drawn off subsequently.

An additional object is the provision of a mechanism of this character which will be simple and inexpensive in manufacture and installation, highly efficient in use, positive in action, durable in service and a general improvement in the art.

With the above and other objects and advantages in view, the invention consists in the details of construction to be hereinafter

more fully described and claimed, and illustrated in the accompanying drawings in which,

Figure 1 is a longitudinal sectional view taken through a still and showing a side elevation of my device in applied position therein.

Figure 2 is a cross-sectional view through the still and showing an end view of my device.

Figure 3 is a perspective view, on a larger scale, of a portion of the spiral support and showing a view of the scraper associated therewith and

Figure 4 is a detail perspective view of one of the scraper devices.

Figure 5 is a detail perspective view of one of the bearing brackets.

Figure 6 is a detail perspective view of the pivot member carried by the arm of the scraper device, and

Figure 7 is a detail cross sectional view through the bearing member and the pivoted end of the scraper device.

Referring more particularly to the drawings the letter A designates a conventional still such as used in oil refining, this still being mounted upon the usual brick work B which defines a fire-box C. The still is provided at its top with a vapor outlet G and in the lower part of one end with a tar outlet pipe E provided with a cut-off valve F.

In carrying out my invention I provide a shaft 10 which is journaled longitudinally of the still A and which is supported by suitable bearings 11 provided on the lower ends of hangers 12 suitably mounted within, and depending from the top portion of, the still. One end of this shaft projects through the end wall of the still and carries a gear 13 or the like by means of which it may be driven. Secured suitably upon the shaft 10 and radiating therefrom at different angular positions are supporting spokes 14 which carry a bar 15 which is of spiral formation and which extends substantially throughout the length of the still as clearly shown in Figure 1. The bar 15 may be of channel iron, angle iron or the like and must of course be of considerable weight depending upon the size of the still. Secured at intervals upon the bar 15 are bearing members 16 which may be mounted at any desired distance apart owing to the fact that the bar 15 is formed throughout

its length with a plurality of holes 17 through selected ones of which may be passed the bolts 18 which hold the bearing members 16. Hinged connected with the 5 respective bearing members 16 are arms 19 which have their free ends carrying cross-members 20 of considerable length and having beveled edges 21. Carried by the outer ends of the cross-members 20 are weights 22.

10 At one end of the still is an inlet pipe 23 which discharges into the interior of the still and through which steam may be passed for the purpose of cleaning out the still.

15 Assuming that the device has been constructed and installed as above described, the operation is as follows:

20 When the shaft 10 is rotated by any desired means, it will be apparent that the spiral formation of the bar 15 will cause sediment within the still to be moved rearwardly by the scraper blades. Owing to the fact that these blades are pivoted, it is apparent that they will drop away from the upper portion of the still but as the bar 25 15 turns and the scraper members are brought toward the bottom or heated portion of the still, the beveled edges 21 will engage the wall of the still and operate to scrape away any carbon deposit practically

25 as soon as it forms in order that there will be no accumulation which could result in the formation of hot spots with the resultant disadvantage thereof. The blades are placed at a sufficient angle to cause the sediment to move toward the rear end and each blade laps over on the surface scraped over by the preceding blade a sufficient distance to take the sediment another blade width rearwardly and so on through the length of 30 the still. The blades falling against the still and then back against the spiral bar will operate not only to keep them free from coke but also to prevent the formation of coke on the bar or supports thereof. In

35 actual practice it is intended that the shaft be rotated at a sufficient speed that every square inch of the heated surface on the still may be scraped every thirty seconds so as to keep the free carbon emulsified to such an extent as to prevent its formation in large masses. Of course after the desired per cent of distillate has been removed from the oil treated in the still, the residue, that is the tar is pumped out through the 40 outlet pipe E provided for the purpose.

Then steam can be turned in through the pipe 23 and the remaining tar can be let out when the temperature has lowered sufficiently to keep the tar from flashing upon 45 exposure to the air. It is not necessary that every particle of the tar and carbon

50 loosened up by the scraper should be re- moved as it is believed that a certain quantity of tar and sediment remaining in the still will be absorbed into the fresh charge 55 of more volatile fuel which is introduced for the next distillation.

From the foregoing description and a study of the drawings it will be apparent that I have thus provided a simply constructed and easily installed automatically acting continuously rotating device which will efficiently operate to prevent the formation of carbon deposits within a still. It is also to be observed that owing to the efficiency of the device there will be a great saving in time and labor effected by its use as the necessity for hand cleaning is almost eliminated. Owing to the simplicity of the construction and the fewness of the parts 60 it is apparent that there is practically nothing to get out of order and that the device will consequently have a long life and satisfactorily perform all the functions for which it is intended.

Having thus described my invention I claim:

1. A still scraping device comprising a shaft journaled longitudinally of the still, a plurality of spokes radiating from the shaft, a bar of spiral formation carried by said spokes and extending substantially the full length of the still, a plurality of brackets adjustably mounted at intervals upon said bar, and a plurality of arms each pivoted within a bracket and carrying transversely arranged weighted scraper blades.

2. A still scraper comprising a shaft journaled longitudinally within a still, a spirally arranged bar supported from said shaft and extending substantially the full length of the still, a plurality of bearing brackets mounted upon said bar at spaced intervals, means for varying the position of the brackets, arms pivoted within the brackets, transverse scraper blades mounted at the outer ends of the arms, and weights at the end portions of the blades for normally maintaining them in a certain position.

3. A rotary scraping device for oil refining stills, comprising a shaft journaled longitudinally of the still, a plurality of spokes radiating from the shaft, a bar of spiral formation carried by said spokes and formed throughout its length with a plurality of holes, bearing members adjustably mounted upon said spiral bar and held by bolts passing through selected ones of said holes, arms pivoted upon said bearing members, and weighted scraper blades carried by the free ends of said arms.

In testimony whereof I affix my signature.

ETHURGE CRAVENS.
